HOUSE NUMBER PLATE

Herbert J. Wylie, Sharp Park, Calif.

Application November 12, 1954, Serial No. 33,065

Term of patent 7 years

(Cl. D72—1)

Fig. 1.

Fig. 2.

Fig. 3.

To all whom it may concern:

Be it known that I, Herbert J. Wylie, a citizen of the United States of America, residing in Sharp Park, in the county of San Mateo and State of California, have invented a new, original, and ornamental Design for House Number Plate, of which the following is a specification, reference being had to the accompanying drawing, forming part thereof.

In the drawing:

Figure 1 is a front elevational view of a house number plate showing my new design,

Figure 2 is a side elevational view thereof; and

Figure 3 is a top plan view.

The dominant features of my new design are shown in solid lines.

I claim:

The ornamental design for a house number plate, as shown and described.
